UNITED STATES PATENT OFFICE.

HENRY A. W. THOMASSON, OF SOUTH BELLINGHAM, WASHINGTON.

AUTOMATIC AIR-INSPIRATOR.

1,259,317.

Specification of Letters Patent. Patented Mar. 12, 1918.

Application filed May 8, 1917. Serial No. 167,255.

To all whom it may concern:

Be it known that I, HENRY A. W. THOMASSON, a citizen of the United States, residing at South Bellingham, in the county of 5 Whatcom and State of Washington, have invented a new and useful Automatic Air-Inspirator, of which the following is a specification.

The present invention relates to an air 10 inspirator or intake device applicable to the intake manifolds or conduits of internal combustion engines, and the objects of the invention are, first, to provide an automatically-closing valve for the manifold and 15 means for regulating the pressure necessary to unseat the valve, and, second, to so assemble the parts that ready access thereto can be had for purpose of replacement and adjustment.

20 The invention is illustrated in the accompanying drawing, wherein:—

Figure 1 is a vertical section of the inspirator, portions being shown in elevation.

Fig. 2 is a plan view of the valve seat and 25 ball receptacle.

Fig. 3 is a cross section on the line 3—3 of Fig. 1.

In carrying out the invention, there is 30 provided a depending air tube 1 having its upper end threaded upon the depending arm of an elbow 2, the other arm of which is provided with an apertured nozzle 3 for breaking up the stream of air, the last mentioned arm of the elbow being threaded or 35 otherwise engaged with the wall of an intake manifold 4 of an engine, for delivering an auxiliary supply of air thereinto.

In order to automatically control the flow 40 of air into the tube 1, a plug 5 is screwed or otherwise engaged into the lower end thereof, and is provided with a wrench-engaging flange 6 bearing upwardly against the lower end of the tube 1, and enabling the plug to be readily applied and removed. This plug 45 5 has attached to its upper surface a plurality of upstanding prongs 7 of arcuate cross section, and spaced apart to provide vertical slots therebetween, said prongs being jointly of cylindrical outline and being

spaced from the wall of the tube 1. The 50 upper ends of the prongs terminate short of the elbow 2, and the plug 5 is provided with a central air inlet aperture 8 and a concaved valve seat 9 surrounding said aperture between the lower ends of the prongs 7. A 55 ball valve 10 is movable loosely within the guide or receptacle formed by the prongs, and one or more balls 11 of suitable weight can be disposed within said receptacle to add additional weight to the valve 10. Thus, 60 there is a column of balls in the receptacle, the lowermost one of which provides a check valve for closing the aperture 8, and said balls can be removed and inserted at will, according to the pressure at which it is 65 desired to have the valve unseat. The lower end of elbow 2 has a notch 12 for permitting air to pass even when the uppermost ball seats against the lower end of the elbow by suction, and the upper ends of the prongs 7 70 are beveled, whereby the balls cannot lodge thereon accidentally.

The weight imposed on the valve 10 should be sufficient to hold said valve to its seat when the suction is low, such as in 75 starting the engine, and since the weight of the ball 10 may not be sufficient, additional balls 11 can be placed within the receptacle provided by the prongs 7. When the suction is increased, the valve will be unseated by 80 the suction, thereby permitting air to flow through the tube 1 and elbow 2 into the manifold. Any suitable number of balls 11 can be used, as may be found necessary, according to the circumstances. The passage 85 of the elbow 2 is of smaller diameter than the balls, whereby the balls cannot be sucked into the elbow, but will be stopped by the lower end thereof, which in being provided with the notch 12 permits the air to pass. 90 By unscrewing the plug 5, it can be readily removed with the balls.

Having thus described the invention, what is claimed as new is:—

An air inspirator embodying an elbow 95 adapted for communication with a manifold and having a reduced intake port at its depending end and notches surrounding said

port, a tube threaded to and depending from the elbow, a plug threaded in the lower end of the tube and having a central aperture and upstanding prongs of arcuate cross section spaced annularly about the aperture, and balls reciprocable between the prongs, the lowermost ball seatable on the valve seat.

In testimony that I claim the foregoing as my own, I have hereto affixed my signature.

Signed at Bellingham, Whatcom county, Washington, April 12, 1917.

HENRY A. W. THOMASSON.
